UNITED STATES PATENT OFFICE.

HERBERT M. STURGIS, OF KANSAS CITY, MISSOURI.

BRUSH.

SPECIFICATION forming part of Letters Patent No. 663,245, dated December 4, 1900.

Application filed April 11, 1900. Serial No. 12,461. (No model.)

To all whom it may concern:

Be it known that I, HERBERT M. STURGIS, of Kansas City, Jackson county, State of Missouri, have invented certain new and useful 5 Improvements in Brushes, of which the following is a full, clear, and exact description, reference being had to the accompanying drawings, forming a part hereof.

My invention relates to brushes; and it consists of the novel construction, combination, and arrangement of parts hereinafter shown, described, and claimed.

Figure 1 is a view in perspective showing my improved brush and the means which I 15 employ to connect the same with a source of water-supply. Fig. 2 is a detail sectional view showing the arrangement of the sprinkling attachment. Fig. 3 shows the under side of a brush having my improved sprinkling 20 attachment secured thereto.

In carrying out my invention I secure within an aperture in the center of the brush-block 1 a cup-shaped sprinkler 2, having integral with its upper edge an annular flange 3. The bottom of the sprinkler is provided 25 with a plurality of apertures 4, and through the sides of the said sprinkler, below the brush-block, are similar apertures 5, the purpose of the latter being to deflect the water 30 through the brush-splints. Upon the upper side of the brush-block is secured an apertured casting 6, in the under side of which is an annular groove 7 for the purpose of receiving the flange 3, there being packing 8 35 above and below the said flange for the purpose of preventing the escape of the water therethrough. The aperture through the said casting is screw-threaded, and into the said casting is threaded a tubular elbow 9, the 40 same being provided with a suitable flange 10 above the casting 6, between which flange and the casting is placed packing 11. Connected to the outer end of the member 11 is a hose 13, of any desired length, which hose 45 carries on its free end a three-way tubular

casting 14, to each fork of which is secured a hose 15, the purpose of said connection being to connect the brush with hot and cold water-pipes leading from any suitable source of water-supply. 50

When it is desired to use the device, it is applied, as shown in Fig. 1, the connections 15 leading from the faucets 16 in the water-pipes 17. The water from either or both sources may then be turned on, and passing 55 through the hose 13 enters the cup 2 and is sprayed through the apertures 4 5, thereby wetting the brush-switches. By this arrangement the necessity of removing the brush from the object to be cleaned is obviated, 60 thereby saving both time and labor and accomplishing the work fully as well or better than can be done by brushes of ordinary construction.

The brush may be used for toilet purposes 65 or for house-cleaning and other purposes.

I claim—

1. A device of the class described, comprising an apertured brush-block, a perforated cup carried in said aperture, an annular flange 70 integral with said cup, a grooved casting for inclosing said flange and means for connecting the device to a source of water-supply, substantially as specified.

2. A brush comprising a brush-block, a 75 perforated cup carried in an aperture in said brush-block, a casting having an annular groove in its under side for receiving an annular flange on the upper edge of said cup, means for securing said casting to the brush-block, an angular tubular casting removably carried by the said grooved casting, and means for connecting the device to a source of water-supply substantially as specified. 80

In testimony whereof I affix my signature 85 in presence of two witnesses.

HERBERT M. STURGIS.
